Primary Examiner — Kimberly Barnes(74) *Attorney, Agent, or Firm* — Cantor Colburn LLP(57) **CLAIM**

The ornamental design for a window beading for helmet, as shown and described.

DESCRIPTION

FIG. 1 is a front view of a window beading for helmet showing my new design;

FIG. 2 is a rear view thereof;

FIG. 3 is a top plan view thereof;

FIG. 4 is a bottom plan view thereof;

FIG. 5 is a right side view thereof, the left side view being a mirror image of FIG. 5;

FIG. 6 is an enlarged cross-sectional view taken along line 6-6 in FIG. 1;

FIG. 7 is an enlarged cross-sectional view taken along line 7-7 in FIG. 1;

FIG. 8 is an enlarged cross-sectional view taken along line 8-8 in FIG. 1 showing only a right-hand part of the window beading;

FIG. 9 is an enlarged cross-sectional view taken along line 9-9 in FIG. 1 showing only a lower right-hand part thereof; and,

FIG. 10 is an enlarged cross-sectional view taken along line 10-10 in FIG. 1 showing only a lower right-hand part thereof.

1 Claim, 10 Drawing Sheets(56)
